UNITED STATES PATENT OFFICE

123,329

DESIGN FOR AN AIR OUTLET FOR VENTILATORS

Maurice Serre, John B. Hewett and Edward A. Schaefer, New York, N. Y., assignors to Anemostat Corporation of America, a corporation of Delaware

Application April 29, 1940, Serial No. 92,032

Term of patent 14 years

To all whom it may concern:

Be it known that we, Maurice Serre, John B. Hewett, and Edward A. Schaefer, citizens of the United States, residing at New York, in the county of New York and State of New York, have invented a new, original, and ornamental Design for an Air Outlet for Ventilators, of which the following is a specification, reference being had to the accompanying drawing, forming part thereof and wherein:

Figure 1 is a perspective view of an air outlet for ventilators showing our new design; and

Figure 2 is a transverse sectional view substantially through the central portion thereof.

The characteristic features of the design reside in an air outlet for ventilators having a series of successively smaller, open-ended, hollow

flaring members spaced successively inwardly of one another and of which the lower end portion of the larger or outermost flaring member is curved first downwardly and inwardly and then upwardly and outwardly and the lower edges of the smaller flaring members are disposed in a plane spaced slightly upwardly from the plane of the lower edge of the larger or outermost flaring member, as best shown in Fig. 2 of the drawing.

We claim:

The ornamental design for an air outlet for ventilators, as shown.

MAURICE SERRE.
JOHN B. HEWETT.
EDWARD A. SCHAEFER.
